UNITED STATES PATENT OFFICE.

WILLIAM A. ROOT, OF NEW YORK, N. Y.

BARBED FENCE-WIRE.

SPECIFICATION forming part of Letters Patent No. 239,553, dated March 29, 1881.

Application filed June 29, 1880. (No model.)

To all whom it may concern:

Be it known that I, WILLIAM A. ROOT, of New York, in the county and State of New York, have invented a new and useful Improvement in Barbed Fence-Wire, of which the following is a specification.

My invention is a barbed fence-wire consisting of two twisted strands and barb-wires, each connected to both strands, and constructed as fully described hereinafter, so as to retain its position and permit ready attachment to the post.

In the drawings, Figure 1 is a side view, showing a section of my improved barbed fence-wire; Fig. 2, a section on the line 2, Fig. 1; and Fig. 3, a section on the line 3, Fig. 1, both sections looking in the direction of the arrow.

The main wire I consists of two strands, *a*, twisted together, and each barb or double barb consists of a strip of wire, which is bent to form two loops or rings, *c c'*, connected by a straight portion, *b*, the barb ends being bent, one to one side and the other to the opposite side of said straight portion, as best shown in Fig. 1. Each loop of the barb receives one of the strands *a*, and the barbs *d e* project beyond said strands in opposite directions, as shown.

As the barb-wire tightly grasps each of the strands I am enabled, while using a comparatively short and light barb-wire, to secure a firm attachment, whether the main strands are close together, as shown at B, Figs. 1 and 3, or widely separated, as shown at A, Figs. 1 and 2.

The described construction, furthermore, results in bringing the plane of the barbs (represented by the line *y*, Fig. 3) parallel to the plane in which lie the portions of the strands *a* gripped by the barb, so that when a nail must be driven adjacent to the barb between the wires *a* it will bring the barb flat against the post without bending the points or prongs.

The within-described form of barb is of such a character as to greatly facilitate the manufacture of the barbed wire by machinery, it being only necessary to lay a straight piece of barb-wire across the continuous strands of straight wire, and then, by a revolving armed sleeve, through which each strand is fed, bend the end of the barb around and over such strand. A machine for this purpose, and specially adapted to lay this peculiarly-formed barb upon the strands, is the subject of a separate application for Letters Patent, allowed on the 12th day of October, 1880, and, in connection with the peculiar formation of the barb, enables me to form the wire expeditiously, cheaply, and secure a firm attachment of each barb in its place.

I claim—

The combination, in a barbed fence-wire, of the twisted strands *a* and barbs *b*, each consisting of a wire bent to form two loops, *c c'*, each receiving one of the strands, a straight middle portion, and points *d e*, extending in opposite directions, substantially as set forth.

WILLIAM A. ROOT.
